UNITED STATES PATENT OFFICE.

WILLIAM DOUGLAS LINSCOTT, OF PIEDMONT, SOUTH DAKOTA, ASSIGNOR OF FOUR-TENTHS TO GEORGE C. HUNT, OF RAPID CITY, SOUTH DAKOTA, AND OLAF OLOFSON LYNG, CHRISTOPHER DERBYSHIRE HOOKER, AND MICHAEL JAMES GILLIGAN, OF PIEDMONT, SOUTH DAKOTA.

ENGINE.

SPECIFICATION forming part of Letters Patent No. 697,346, dated April 8, 1902.

Application filed June 7, 1901. Serial No. 63,571. (No model.)

To all whom it may concern:

Be it known that I, WILLIAM DOUGLAS LINSCOTT, a citizen of the United States, and a resident of Piedmont, in the county of Meade 5 and State of South Dakota, have invented a new and Improved Engine, of which the following is a full, clear, and exact description.

This invention relates to an engine adapted to be driven by fluid under pressure, and particularly adapted for use in connection with steam.

It comprises a number of rotary pistons attached to a common shaft and fitted within a cylinder-like casing. The casing and piston 15 are provided with certain peculiarly-formed ribs on which the steam acts, whereby the motive force is produced.

This specification is a specific description of one form of the invention, while the claim 20 is a definition of the actual scope thereof.

Reference is to be had to the accompanying drawings, forming a part of this specification, in which similar characters of reference indicate corresponding parts in all the views.

25 Figure 1 is a longitudinal section of the invention. Fig. 2 is an elevation of one of the sections of the casing. Fig. 3 is an elevation of one of the pistons. Fig. 4 is an end elevation 30 of the cylinder-heads looking in the direction of the arrow on the line 4-4 of Fig. 1, and Fig. 5 is a sectional view showing the form of the ribs and the action of the steam thereon.

a indicates suitable bearings in which is 35 arranged to turn the engine-shaft *b*.

c and *d* indicate, respectively, the cylinder-heads, which are stationary and which are arranged one at each end of the engine just inside of the bearings *a*. The cylinder or casing 40 itself is made up of a number of annular sections *e*, which comprise imperforate outer walls joined together, the parts *c*, *d*, and *e* being held by tie-rods *f*, engaged with eyes on the cylinder-heads. (See the elements *d*³ in

45 Fig. 4.) Each section *e* of the casing has a web-like portion made up of a number of annular series of ribs or partitions *e'*, between each of which series are formed circular partitions *e*². These web-like portions of the sec-

tions *e* are set at one side of the sections, (see 50 Fig. 1,) thus forming cavities in which are received the working or web portions of the pistons. These portions of the pistons, as indicated in Figs. 1 and 3, are made up of a number of annular series of radial ribs or vanes *g*, 55 said annular series of ribs being separated by circular partitions *g'*. This forms a structure similar to the structure produced by the parts *e'* and *e*², and the various circular partitions *e*² and *g'* are respectively in registry 60 with each other, steam-tight connections being formed by ribs produced on the edges of the partitions *g'* and fitting loosely in corresponding grooves formed in the edges of the partitions *e*². Each piston also comprises an 65 elongated hub *g*², these hubs being keyed to the shaft *b* and being projected beyond the web portions of the pistons, so as to form a support for the web portions of the sections *e* of the casing or cylinder. At one end of 70 the engine a bushing or spacing collar *h* is fastened to the shaft *b* and lies within the web portion of the adjacent section *e* of the cylinder to support the same, since at this point there will be no support furnished by 75 a piston-hub.

i indicates the motive-fluid feed-pipe and *k* the exhaust-pipe. The feed-pipe *i* communicates with an annular cavity *c'*, formed in the piston-head *c*. (See Fig. 1.) This cavity 80 communicates and feeds steam to the numerous annular series of steam-passages formed in the cylinder-webs and in the pistons by the parts *e'* *e*² and *g g'*. Reference to Fig. 2 will show that each of these numerous series of 85 passages are in longitudinal line with each other, and therefore form a steam-passage extending completely through the engine. At the end of the engine opposite the pipes *e'* and *k* the head *d* is formed with an annular return-port *d'*, which leads the steam back into the next series of passages, through which the steam passes to a port *c*² in the head *c*, such port being similar to the port *d'*. The head *d* is provided with a second port *d*², similar to the port *d'*, and this second port leads the steam to the outermost steam-passage, which port communicates with an annular cavity *c*³ 90 95

in the head *c*, such cavity in turn communicating with the exhaust-pipe *k*.

Reference to Fig. 5 will show the form of the ribs or vanes *e*' and *g*. These vanes are preferably V-shaped, and assuming that the steam is passing in the direction of the arrows in this view and that the two end sections shown in the view are the stationary web portions of the cylinder, it will be seen that the steam acting by impact and reacting on the ribs or vanes *g* will turn the pistons in the direction of the arrow in Fig. 5. The steam has a continuous course through the various passages of the engine, thus deriving from the steam all the energy therein and driving the pistons continuously in one direction, which in turn imparts movement to the shaft *b*. Obviously any number of annular steam-passages could be formed in the engine. It will be apparent that each annular series of ribs *e*' and *g* forms a tubular steam-passage extending throughout the length of the engine. One of these passages is sufficient to fulfil the principle of my invention; but obviously they could be multiplied to any extent desired.

Various changes in the form, proportions, and minor details of my invention may be re-

sorted to without departing from the spirit and scope of my invention. Hence I consider myself entitled to all such variations as may lie within the scope of my claim.

Having thus described my invention, I claim as new and desire to secure by Letters Patent—

An engine, comprising a cylinder having an inwardly-disposed web-like portion, a shaft running centrally through the cylinder, a piston fastened to the shaft at each side of said web-like portion of the cylinder and having web-like portions lying alongside of the web-like portion of the cylinder, all of such web-like portions having registering annular or tubular steam-passages with V-shaped ribs or vanes therein, said vanes being set oppositely in each of said web-like portions, and means for conducting the motive fluid to and from the said steam-passages.

In testimony whereof I have signed my name to this specification in the presence of two subscribing witnesses.

WILLIAM DOUGLAS LINSCOTT.
